UNITED STATES PATENT OFFICE.

ROBERT J. KYLE, OF NEW YORK, N. Y., ASSIGNOR OF TWO-THIRDS TO
CHARLES E. VAN VLECK, OF MONTCLAIR, NEW JERSEY, AND JOSEPH
L. PORTER, OF NEW YORK, N. Y.

GARMENT-SUPPORTER.

SPECIFICATION forming part of Letters Patent No. 359,616, dated March 22, 1887.

Application filed October 27, 1886. Serial No. 217,301. (No model.)

To all whom it may concern:

Be it known that I, ROBERT J. KYLE, a citizen of the United States, residing in New York city, in the county and State of New York, have 5 invented a new and useful Improvement in Supporters for Garments and Similar Articles, of which the following is a full, clear, and exact specification, reference being had to the accompanying drawings and the letters and figures 10 of reference marked thereon, which form a part of this specification.

This invention relates to an improvement in clasps or catches for supporting garments, such as hose or any other similar articles; and 15 it consists in the devices hereinafter described and claimed.

In the drawings, Figure 1 is a top or plan view of my improved catch. Fig. 2 is a side elevation of the device shown in Fig. 1. Fig. 20 3 is a view of the under side of the catch. Fig. 4 is a sectional view of the catch on the line 4 4 of Fig. 1. Fig. 5 is a vertical section of my supporter, showing the same attached to the fabric to be supported, and showing the 25 two leaves of the supporter made in separate pieces, but held together at the top by the webbing. Fig. 6 is a side elevation showing another mode of attaching the leaves of my supporter to each other. Fig. 7 is an enlarged 30 view of a portion of the leaf b, and a sectional view of the movable button, showing the latter with a square hub.

Similar letters indicate similar parts in the different drawings.

35 My catch or fastener consists of the upper and lower leaves, a and b, and the movable button or wedge c. I prefer to make the leaves a and b in about the form shown and from spring-brass or other suitable spring metal 40 struck up in the proper form. (See Figs. 1 and 2.) The leaves a and b have slots d at their ends for attachment to the webbing, as shown. I prefer to so make these leaves that in their normal position the elasticity of the metal will hold the leaf a up from the leaf b, as shown in Fig. 2. The button or wedge c moves in a slot in the leaf b, being held in said slot by means of shoulders, as shown in Fig. 4.

The lower head or shoulder of the button projects below the surface of the leaf b, thus enabling the button to be easily moved from below by the finger. I make the slot in the leaf b tapering toward the inner end, so that when the button c is pressed up into that end of the slot it will fit snugly enough there to prevent 55 it from dropping down to the other end of its own weight.

The leaf a is provided with a slot or opening in the manner shown, large enough at the inner end to permit the head of the button c 60 to pass through it, but at the other end too narrow to permit the passage of the button-head, but wide enough to receive the neck of the button and the surrounding fabric, and thus allow the button to be pressed down to 65 that end. I make in that narrower end of the slot a countersunk track or groove, upon which the head of the button can slide. This countersinking enables the head of the button to wedge in the surrounding fabric more tightly. 70

Instead of making the two leaves a and b in a single piece, the leaves can be made of separate pieces and attached together by a piece of metal rolled in the form of a hinge, as shown in Fig. 6; or they can be attached in 75 any other suitable manner, as by being sewed to the same piece of webbing. (See Fig. 5.)

In using my supporter the garment or cloth that is to be supported is passed in between the two leaves a and b and over the head of the 80 button c, preferably for some distance. This in itself tends to push the button up to the inner end of the slot in the leaf b. When the button has been brought to that position, the leaf a is forced down upon the cloth and leaf 85 b, and the head of the button c, with the fabric above and around it, is thus forced through the slot in the leaf a. Then the button c is pressed down into the lower part of the slot in the leaf a, and thus engages the garment or 90 cloth above and around it in a firm grip. The act of stretching the webbing attached to the leaves a and b will of itself tend to pull the leaves away from the garment, and thus cause the button to be forced down into the lower 95 end of the slot in the leaf b. If the counter-

sink-track is used the cloth will be held more firmly, and the button can be more easily pressed down into the lower part of the slot.

If the leaves *a* and *b* are made from spring metal, when the catch is fastened to the garment or cloth to be supported the elasticity of the metal causes the leaf *a* to press up tightly against the head of the button *c*, and thus to hold the cloth or garment more firmly and prevent the button *c* from slipping up out of the narrow portion of the slot in the leaf *a*. For this reason I prefer to make my catch in this form.

When my supporter is not made from spring metal in a single piece, but is made as shown in Fig. 5, or as shown in Fig. 6, in attaching it to the fabric to be supported the leaf *a* has to be raised by the finger above the top of the button *c* before the fabric can be inserted.

Instead of making the shank or neck of the button *c* round, as shown in Fig. 4, the sides of the shank may be made flat or straight, so that the button cannot revolve in the slot in the leaf *b*, as shown in Fig. 7. This will help to prevent the cloth from slipping over the button.

What I claim as new, and desire to secure by Letters Patent, is—

1. A catch or supporter consisting of two leaves or parts, in a slot in one of which a button is movably attached by two shoulders on the button below the head of the button, one above and the other below the leaf, and in the other of which there is a slot with a wide and narrow portion adapted, respectively, to receive and hold the head of the movable button and the surrounding fabric, substantially as and for the purposes set forth.

2. A catch or supporter consisting of two leaves or parts, a slot tapering at its upper end in one of said leaves, and a movable button working in said slot, and another slot in the other leaf of the catch, having a wide and a narrow portion adapted, respectively, to receive and hold the head of the movable button and the surrounding fabric, substantially as and for the purposes set forth.

3. A catch or supporter consisting of two leaves or parts, a movable button working in a slot in one of said leaves and having two shoulders, one above and the other below the leaf, and having a square or rectangular hub between the shoulders, and another slot in the other leaf, having a wide and a narrow portion adapted, respectively, to receive and hold the head of the movable button and the surrounding fabric, whereby the button is prevented from sinking down in or turning around in its slot, substantially as and for the purposes set forth.

4. A catch or supporter consisting of two leaves or parts, to one of which a button is movably attached, and in the other of which there is a slot with a wide and a narrow portion adapted, respectively, to receive and hold the head of the movable button and the surrounding fabric, the narrow portion of said slot having a countersunk track to receive the head of the button, substantially as and for the purposes set forth.

ROBERT J. KYLE.
